(57) **CLAIM**

The ornamental design for a vehicle fairing bezel as shown and described.

DESCRIPTION

FIG. 1 is an isometric view of a vehicle fairing bezel, showing our new design.

FIG. 2 is a front elevational view thereof.

FIG. 3 is a rear elevational view thereof.

FIG. 4 is a right side elevational view thereof; and,

FIG. 5 is a top plan view thereof.

A second embodiment, being a mirror image of the vehicle fairing bezel shown in FIGS. 1-5, is claimed but not shown. The broken lines depict portions of the vehicle fairing bezel that form no part of the claimed design.
